FILING CABINET

Zemach Auerbach, New York, N. Y.

Application December 12, 1928, Serial No.
325,533. Renewed January 27, 1933

15 Claims. (Cl. 45—2)

The object of my invention is to provide a filing cabinet having movable holders adapted to slide in relation to the cabinet in order to bring the contents into position for examination or for writing, so combined with the cabinet that when in closed position the cabinet will take up much less space than the ordinary cabinet having longitudinally sliding drawers. The present cabinet of a given capacity will require less space in a room than the ordinary sliding drawer cabinet when in closed position and in addition, when the holders are drawn out to active position the overall depth of the cabinet and the holder is considerably less than the overall depth of the ordinary horizontally sliding door cabinet in open position.

In addition to providing a more compact type of cabinet, it is the object of my invention to provide a cabinet in which the holders may be drawn out into active position with the least effort on the part of the operator, which is an important factor where the holders must necessarily be drawn out and returned repeatedly during the day's work. In one form of the device the holders lie in a vertical plane when in inactive position and they are moved upon abutment pins or supports when being moved into extended or active position, so that the holders rock against the supports and reduce the effort necessary to move the holders into active position.

In another form of the device shown herein the holders or trays are counterbalanced in order to reduce to a minimum the effort necessary to move the trays or the holders between the inactive position and the extended or active position, and vice versa.

Another object of the invention is to provide a cabinet having a number of trays or holders adapted, when in folded position, to lie in adjacent, parallel, vertical planes in compact relation, which holders or trays are adapted to slide in relation to guiding members in the cabinet, so that they may be brought into a horizontal position projecting somewhat over the front edge of the cabinet where they may be individually opened like a book to permit the contents to be examined or to permit the operator to write on cards, sheets, or other members carried by the holders. There is an extensible support or shelf for the holders, having folding leaves to support the holder in horizontal position. On these leaves there are extension leaves extending downwardly from the first mentioned leaves at the side of the cabinet to rest against the same and support the horizontal leaves in position for writing

and similar purposes. These supports are adapted to fold and to be returned in compact form when the holder is returned to inactive position.

Another object is to provide a cabinet having a number of holders adapted to lie in vertical planes in compact relation and to be moved individually into writing position with individual counterweights for counterbalancing the individual holders. Other features and advantages will be set forth in the following detailed description of my invention.

In the drawings forming part of this application:

Figure 1 is an end elevation of a filing cabinet embodying my invention in the preferred form and in this view the parts are shown in the inactive or closed position.

Figure 2 is a similar view illustrating one of the holders raised and extended into horizontal position with the leaves of the sliding shelf opened out to form a rest for the leaves or trays of one of the movable holders.

Figure 3 is a front elevation of the same device with the parts in the same position as shown in Figure 1.

Figure 4 is a vertical, sectional view on an enlarged scale of the upper portion of the cabinet and is taken on the line 4—4 of Figure 5.

Figure 5 is a sectional view taken on the line 5—5 of Figure 4.

Figure 25 is a perspective view of a portion of the holder and showing the guide or sleeve which engages the track, and

25 Figure 26 is a perspective view of the same parts taken at a different angle.

I will first describe the form of my invention shown in Figures 1 to 18 inclusive. I have shown a cabinet mounted on a base 1 which is provided with casters 2 to permit the cabinet to be moved on the floor.

30 Extending upwardly from the back end of this base there is a rear wall 3 extending the full depth of the cabinet and at each side there are panels 4 having a narrow lower portion 5 to form the lower end of a pocket or channel in which the movable weights may move to a position near the base 1. These panels 4 are shown as having a slanting lower edge 6 conforming substantially with the position of one 35 end of the holders when they are enclosed in the cabinet. The front panel 7 extends upwardly and in an oblique position from the edges 6 and terminates adjacent the top horizontal edges 8 which is the top of the main portion of the cabinet. The two side panels, the slanting front panel 7, together with the back wall 3 form an enclosing chamber to receive and contain the several holders.

35 The rear wall 3 of the cabinet extends upwardly above the plane of the edge 8 and the side panels have extensions 9 at the rear and disposed at each side of the rear wall to a point where the side panels are provided with forwardly extending horizontal portions 10 which 40 form an overhanging compartment in which certain rollers may move on the horizontal tracks. I have shown a sliding drawer 11 adapted to slide in the compartment formed between the horizontal sections 10 which compartment preferably is closed by a top wall 12 and I have also shown an electric lamp 13 disposed in this compartment under the sliding drawer and near the forward edge of the compartment. This lamp is adapted to radiate downwardly onto the 45 top of the holders to facilitate reading any matter on the rear ends of the holders and to facilitate writing any matter upon sheets, cards or other members carried by the holders.

50 In this form of the invention I have shown a number of vertical posts 14 mounted in the cabinet adjacent each other and extending parallel with the back wall but spaced therefrom to provide guideways for the movable weights. These posts are shown as composed of a rear wall or web 15, side walls 16, and inturned flanges

17 at the forward edges of the side walls, the edges of these flanges being separated to provide a space in which the cables or cords which are connected with the holders may move freely. Between adjacent posts 14 80 there are vertically arranged parallel partitions 18 which divide the cabinet chamber into a series of vertical compartments 19 for receiving the individual holders. These vertical partitions extend between the posts 14 and project rearwardly beyond them, as shown at 20, to form guides for guiding the vertically moving counterweights 21 and to keep these separated from each other. Adjacent the upper end of each of these posts there is mounted a sheave 22 on a bracket 23 attached to the rear wall 15 of each post; and over these sheaves the individual cables or cords 24 are adapted to engage. One end of each cord or cable is attached to one of the counterweights 21 and the other end is attached to one of the 90 holders as will be more fully described herein-after. Adjacent the upper ends of each of the posts 14 there is a forwardly extending horizontal extension 25 which is preferably formed like the posts in cross section with a top wall 26, side walls 27, and inwardly turned flanges 28, the latter having their opposed edges spaced apart at the under side to permit a portion of the holder to travel longitudinally through this space. These forward extensions of the posts are arranged in the upper compartment of the cabinet and form the tracks for the several rollers of the movable holders.

95 Within the cabinet and adjacent the oblique front wall thereof I have shown horizontally disposed bars 29 having freely revolvable sleeves 30 thereon disposed between the adjacent vertical partitions, these sleeves forming antifriction bearings against which the forward ends of the several holders may rest and move while the 105 holders are being moved from inactive to active position and vice versa.

110 The several holders preferably employed in this device are constructed as follows: There is a bar or rail 31 having a horizontal portion 32 with an 115 upwardly extending rear arm 33 projecting preferably at right angles to the horizontal portion; and on the upper end of the latter there are journaled the two parallel rollers 34 on the axle 35. One end of one of the cables or ropes 24 which 120 are connected with the counterweights is connected at 36 with the bar 33 of the holder. Preferably, the bar 32, 33 is composed of a channel shape member to make it rigid or non-bending and as shown herein this consists of a horizontal web 37 with the parallel side flanges 38. (See Fig. 18. It will be understood that the particular type of metal here shown and described is not imperative. The hinged members or leaves or 125 trays 39 of the holder are pivotally connected with the bar or frame to permit them to be hinged or swung like the leaves or covers of a book; and for this purpose I have shown two parallel members 39 for each holder, which may be in the 130 form of leaves, boxes or trays, according to the character of the material to be contained therein. Each of these is pivotally mounted at one end on a pintle 40 attached to the rear vertical member 33 of the bar of the holder and at the forward 135 end of each leaf member there is a detachable pintle constructed as follows:

140 There is a small box or housing 41 attached to the bar 32 and within this housing there is a longitudinally sliding pintle 42 extending through and having its bearings in the end walls of the 145

box; and there is a coiled spring 43 contained within the box and surrounding the pintle, which spring presses at one end against a flange 44 on the pintle and against the forward wall of the 5 box in order to urge the pintle to the left hand position shown in Figure 17. One end of the pintle 42 projects through the rear wall of the box and beyond the same into an aperture in one of the leaves or trays 39 to form, with the fixed 10 pintle 40 the two hinge members for the leaf or tray whereby the latter may swing from the full line position shown in Figure 15 to the horizontal dotted line position and vice versa. One end of the pintle 42 projects through the front 15 wall of the box 41 and it is provided with a finger-piece 45 which may be grasped for the purpose of drawing back the pintle against the resistance of the spring 43 sufficiently to withdraw the forward end of the pintle from the leaf or tray in 20 order to permit the latter to be disengaged from both pintles. This permits the leaf or tray to be removed from its holder and to permit another one to be put in its place. From this it will be observed that the leaves or trays may be very 25 quickly detached from their holders to bodily remove the trays or leaves with their contents whenever it is desired to transfer material from one cabinet to another. There is a depression 46 in the top wall of the box 41 to engage the flange 30 44 and temporarily hold the pintle 42 in retracted position. The forward end of the bar 32 of the holder is shown provided with a loop 47 to serve as a handle for gripping the holder at the forward end when it is desired to move it.

35 It will be understood that in the form of the invention shown herein there are two pintles 40 at the rear of the holder frame and there are two pintles 42 at the forward end, both of the latter being arranged in the box 41 the duplicate pintles 40 being adapted to pivotally support a pair of the leaves or holders, as shown in Figures 13 to 15, if the invention is embodied in the form herein shown.

45 The rollers 34 on the rear upper end of the holder frame are adapted to travel vertically within the pockets of the rear posts 14 and to be guided by the flanges 17 thereof and these rollers are also adapted to pass from the channels of the vertical posts into the channels of the 50 upper horizontal extensions 25 and will be there guided by and rest upon the flanges 28 while the rollers are moving horizontally in the upper compartment.

55 I have provided a novel shelf or support which acts as a cover for the cabinet and which also serves to support the leaves or trays of the holders whenever these are in their raised or active positions and it consists of the following: There is a U-shaped frame composed of a wire 48 which is disposed partly in a tubular socket around three sides of a shelf 49. This shelf is preferably provided with a downwardly extending flange 50 on its two sides and front which flange is adapted to overlap the top edge of the front wall of the cabinet and portions of the side panels 4 to form a cover for the forward part of the cabinet when in closed position and to form an extending shelf for the holders when the latter are in their active position.

70 There are rearwardly extending rails 51 projecting from the shelf 49 and these are provided with spaced, tubular socket members 52 through which the extended ends of the U-shaped wire 48 project, these tubular sockets forming halves 75 of hinge members. There are folding leaves 53

one at each side of the cover member, and these have sockets or ears 54 which lie between the sockets 52; and the extensions of the wire 48 also pass through these sockets or ears, so that a hinge connection is provided between the leaves 53 and the rail members 51 on which the leaves may pivot in the manner hereinafter described. I prefer to provide at the rear ends of the leaves 53 supplemental or extension leaves 55 which are hinged to the leaves 53 by means of the hinges 56. I have shown flanges 57 extending laterally from the bars 51 at their bottom edges, and these are adapted to engage and slide in relation to the horizontal tracks 58 arranged in the cabinet for the purpose of slidingly supporting the extension shelf.

Operation

I will here describe the operation of the device constructed in accordance with Figures 1 to 18 inclusive. In Figure 1 the cabinet is shown in closed position. In this case all of the holders have their leaves or trays 39 folded up in parallel relation and each holding device extends into one of the compartments 19 of the cabinet with one corner of the frame of the holder resting in the socket of the block 60 in the lower corner of the cabinet; and the upper portions of the holder frames lie against the sleeves on the bar 29. In this position the several holders are slightly inclined to the vertical.

One of the cables or cords 24 extends from the point of connection 36 with each holder frame upwardly through the channel in a post 14 and thence over the sheave 22 and downwardly on the opposite side of the sheave. The other end of each cable or cord is connected with a counter-balance weight 21 which is in the upper position shown in dotted lines in Figure 1 when the holder is in the position indicated in this figure. The cable or cord is prevented from disengaging from the sheave by a small guide pulley 61 arranged near each sheave. When the cabinet is in this closed position the leaves 53 of the movable shelf are folded in toward each other, as shown in Figure 9, so that these leaves and the shelf 49 form a complete cover for the top of the cabinet. The extension leaves 55 are turned upwardly, as shown in Figure 9, and as shown in Figure 1, so that they form a closure for the portion of the cabinet formed by the upper extensions 9 of the cabinet, and below the horizontal section 10. In this closed position the front to back dimension of the cabinet is much less than one of the vertical filing cabinets having horizontally sliding drawers of the same capacity.

If it is desired to examine the contents of one of the holders, the sliding cover 49 is moved forwardly to the position shown in Figure 2, so that this member projects forwardly beyond the cabinet; and the two leaves 53 are then swung on their hinges into the position shown in Figures 2 and 10, so that these leaves project laterally at the sides of the cabinet and leave a central opening as indicated at 62 in Figure 10 for the drawing out of one of the holders.

When the leaves 53 are thus folded back the extension leaves 55 are moved from the upwardly extending position shown in Figure 9 to the downwardly extending position shown in Figures 2 to 10 and these extension leaves then rest against the side walls 4 of the cabinet, as shown in Figure 2, and in this position they serve as brackets to support the leaves 53 in horizontal position. There is now a forwardly extending shelf pro-

jecting beyond the front of the cabinet consisting of the member 49 and the two leaves 53 extending horizontally at the sides of the cabinet, and the extension leaves 55 resting against the sides of the 5 cabinet to hold the leaves 53 in a horizontal position. Any one of the holders in the cabinet may now be withdrawn and for this purpose the operator will grasp the handle 47 of any holder which he or she desires to withdraw and pulls upwardly 10 and forwardly on the handle. The particular holder and its leaves move upwardly against the sleeves 30 until the holder is near the top of the cabinet when the holder begins to turn against the rollers 30 and finally the holder reaches a 15 horizontal position, as shown in Figure 2, and rests on the extension shelf 49. While the holder is being raised, the counterweight 21 is exerting an upward pull on the rear end of the holder frame sufficiently to lift the major portion of the 20 weight of the holder, so that very little exertion is required to move the holder into the open position. As the holder moves upwardly, the rollers 34 on the upper, rear corner of the holder frame travel in the channel of the post 14 and the counterweight 21 moves downwardly in the space between the extensions 20 of two of the partitions and behind one of the posts 14. When the rollers 25 34 reach the upper end of the post 14 they come into line with the flanges 28 of the horizontal extensions 25 at the time the holder arrives in a 30 horizontal position.

If the matter to be examined in the holder is in the forward portion of it, the holder need not be drawn forwardly over the movable shelf 49 but 35 if the matter to be examined is near the rear end of the holder it may be desirable to draw the holder forwardly into the position shown in Figure 2 where the forward end will project over and rest upon the shelf 49, as shown in this figure. 40 The leaves or trays 39 of the holder may then be swung outwardly and downwardly on their pintles, as shown in dotted lines in Figure 15, so that they rest upon the extension leaves 53 in an open position like the leaves of a book. The operator may 45 then examine the contents of the holder or remove or add sheets, cards or other members thereto, or may write upon any articles in the holder, the leaves 53 forming a rest for the holder during the writing operation. The extension leaves 55 support the leaves 53 in the horizontal position with sufficient rigidity to support the holder while these operations are being performed. The lamp 13 will light up the contents 50 of the holder to facilitate writing on or observation of the contents. When the holder is moved into the horizontal position and the rollers 34 reach the upper portion of the posts 14 they come 55 into line with the horizontal flanges 28 of the post extensions, so that if the holder is moved forwardly into the position shown in Figure 2, the rollers 34 rest upon and travel along the flanges 28 so that the rear portion of the holder is supported from these rollers, as shown in Figure 2. Even when the holder is extended, as 60 shown in Figure 2, the overall depth of the cabinet and the holder is less than the ordinary drawer cabinet with the drawer fully extended.

After the operator has finished with the particular holder which was withdrawn, the leaves or trays 39 may then be swung into vertical position, as shown in full lines in Figure 15, whereupon the holder may be pushed backwardly to 65 return it to its compartment in the cabinet. If the holder was fully withdrawn, as shown in

Figure 2, then upon the first part of this movement the rollers 34 will move backwardly on the flanges 28 until they enter the channel of the post 14, whereupon these rollers will move downwardly in these channels until the holder returns to the position shown in Figure 1. During this downward movement of the holder, its counterweight 21 moves upwardly. The operator may then proceed to withdraw any of the other holders into open position for the purpose of examining the contents or adding to or withdrawing from the same, or writing thereon, and the operations above described will be repeated as to any of the other holders, each one moving in its particular compartment in the cabinet under the influence of its individual counterweight. When all of the 80 holders have been returned within the cabinet, the latter may be closed, in which case the leaves 53 will be folded over from the position shown in Figure 10 to the position shown in Figure 9, and the extensible panels 55 will be folded up into the vertical position illustrated in the latter figure, whereupon the complete extension shelf will be slid backwardly along the rails 58 until the flange 48a stops against the front wall of the 85 cabinet. The shelf 49 and the leaves 53 will form a complete top closure for the cabinet and the extension leaves 55 will close the space in front of the upper extensions of the posts 14 and between the top cover and the under wall of the 90 overhanging top member of the cabinet.

The sliding drawer 11, which may contain a card index of the contents of the cabinet, or any other material, may be opened at any time desired and its operation is independent of the 95 operation of the other devices.

Referring now to the modified construction shown in Figures 19 to 26 I have shown a base 64 with legs 65 extending upwardly therefrom, and supporting the cabinet, consisting of a rear wall 66, a bottom wall 67, an oblique front wall 68, and the side walls 69; and within the compartment formed by this body or cabinet there are dividing partitions 70 vertically disposed and dividing the interior of the cabinet into the several compartments 71 for containing the individual holders. On one side of each partition there is arranged a track for guiding the lower end of the frame of the holder, the track being composed of the portion 72 which is riveted or bolted against the face of the partition and laterally extending flanges 73 at each side which are raised from the plane of the partition to permit the sleeves on the holders to pass around the edges of the flanges and to slide in relation thereto. The shape of the tracks is shown in Figures 19 and 20. They extend from the upper portion 74 at a point located nearly midway of the cabinet front to back, and from there they extend downwardly and rearwardly along the portion 75 and they then curve at 76 downwardly and forwardly to a point adjacent the bottom end of the front wall of the cabinet.

Each holder consists of a bar or rod 77 provided with a handle portion 78 on its forward end and with a sleeve on its rear end to engage one of the tracks.

The leaves or trays 79 of the holder are pivotally mounted on the bar 77 by means of pintles 80 so that they may hinge in a manner similar to the corresponding parts of the first described form. At the rear end of each bar 77 there is a bracket 81 secured permanently to the bar, which bracket has an upwardly extending portion 82 adapted to lie between the adja- 145 150

cent edges of the leaves or trays 79 of the holder. There is a bracket formed of a metal plate having a portion 83 secured to the wall 82 of the bracket 81, thence extending laterally at 84 and 5 thence rearwardly at 85 and thence downwardly at 86, there being a flap formed by cutting this plate and bending the tongue 87 at right angles to lie between the bracket 81 and the bar 77 and to be held assembled with it by the rivet 88. 10 On the lower end of the member 86 there is pivoted a sleeve comprising a flat plate 89 having flanges 90 at each side turned inwardly toward each other to overlap the flanges 73 of one of the guiding rails. This sleeve is pivoted 15 on the pin 91 so that it may turn in relation to the holder as it follows the curved track.

I have shown horizontally extending bars 92, 93, 94, 95 disposed across the cabinet and provided with individual sleeves or rollers 96 which 20 revolve freely on these bars between the several partitions 70 and these several sets of rollers form partial supports for the holders while they are partly or wholly within the cabinet. There is a hinged cover 97 for closing part of the top 25 of the cabinet and mounted on the rear hinge 98. This partial cover may be provided with plates 99 and between these and the wall of the cover various index cards or tabs 100 may be inserted to indicate the contents of the several 30 holders.

The cover 97 is so proportioned as to close only the rear portion of the cabinet, the forward portion being closed by a sliding cover 101 which may be moved forwardly in the tracks 102 for the purpose of providing, as shown in Figure 23, an extension shelf at the front of the cabinet on which the holders may be partly supported.

The operation of the modified device above 40 described is as follows: When the cabinet is closed, as shown in Figure 19, the holders are disposed in vertical position in the several compartments 71 with the holders resting on the abutment rail 103 and with the sleeve 89 of each 45 holder at the lower end of the track. The bar 77 of each holder at this time may rest against the rollers on the lower rod 92. If it is desired to operate one of the holders, the sliding shelf 101 is first moved forwardly, as shown in 50 Figure 23, to open the top of the cabinet, and the hinged cover 97 is preferably swung upwardly as well. The operator then grasps the handle 78 of any one of the holders which is to be operated and draws upwardly and forwardly on the handle to raise the holder into the horizontal position shown in Figure 23. During this movement the sleeve 89 is guided along the track but the holder is pivotally connected with this sleeve so that it may rock in relation to it. As 55 the holder moves upwardly it first rests against the rod 92 and as it moves further, as indicated in Figure 20, the holder temporarily rests against both rods 92, 93. As the holder continues to move upwardly, it rocks in relation to the rod 93 and then temporarily rests on this rod and the upper rod 94.

Further upward movement of the holder causes 60 it to rest against the rod 94 and the uppermost rod 95 and finally against the latter only; so that 65 as the holder is fully withdrawn and its sleeve reaches the upper end of the track, the holder will project horizontally or substantially horizontally onto the projecting shelf 101. The leaves 70 or trays 79 of the holder may then be opened 75

up or laid flat, as shown in Figures 23 and 24, permitting access to the contents thereof. When the operator has finished with this particular holder the leaves or trays are folded up or closed and the holder may be returned into the cabinet by simply pushing rearwardly thereon. Any of the other holders may be operated in the same manner. It will be apparent that the movement of the holder, when rising from the cabinet and returning therein, is guided principally by the track, but the several rods 92-95 not only serve to guide the holders in conjunction with the track but they also serve as abutments for the holder to rest against while being withdrawn from the cabinet in order that they will partly support the holders while they are being withdrawn.

The box 41 which contains the movable pintles is adapted to prevent the shifting lengthwise of the leaves or trays 39 in one direction, so that they cannot accidentally disengage from the pintles. If the pintles 42 were depended upon to limit the longitudinal movement of the leaves or trays 39 or in other words, form the abutment at one end, then because of the spring pressure the leaves would disengage from the frames; but with the box 41 acting as an abutment in one direction, the pintles 42 are only required to serve in conjunction with the pintles 40 as pivotal members.

When the holders are in the extreme open 105 position shown in Figure 2, if they contain cards adapted to be turned backwardly, there is room behind the holder, when in the position shown in Figure 2, for the cards near the rear end of the holder to be turned backwardly to permit writing 110 thereon.

From the above it will be apparent that I have provided a cabinet wherein the holders when in closed position lie with their major dimension vertical or nearly vertical, so that the front to rear depth of the cabinet need be only slightly greater than the vertical depth of the holders. But when the holders are in open position they are accessible for their full length and the overall depth of the cabinet and holder at that time is much less than the overall depth of a sliding drawer cabinet with the drawer fully opened.

Having described my invention, what I claim is:

1. In a device of the class described a cabinet 115 for holding a group of holders, holders adapted to lie in substantially vertical position within said cabinet and to be withdrawn into a substantially horizontal position at the top of the cabinet, and means for guiding said holders in their movements between the vertical position and the horizontal position said guiding means being adapted to cause the lower ends of said holders to travel near the rear of said cabinet when said holders are being moved between the vertical and horizontal positions, and adapted to permit said holders to turn from the vertical into the horizontal position.

2. In a device of the class described a cabinet 120 for holding a group of holders, means for dividing the cabinet into a plurality of compartments for said holders, holders adapted to lie in substantially vertical position within said compartments of the cabinet and adapted to be individually withdrawn into a substantially horizontal position at the top of the cabinet, and means for individually guiding said holders in their movements between the vertical position and the horizontal position said guiding means being adapted to cause the lower ends of said holders to travel near the rear 125

of said cabinet when being moved between the vertical and horizontal positions and adapted to permit said holders to turn from the vertical into the horizontal position.

5. 3. In a device of the class described a cabinet for holding a group of holders, holders adapted to lie in substantially vertical position within said cabinet, said holders being of greater length than the front to rear dimension of the upper portion 10 of said cabinet, said holders being adapted to be withdrawn into a substantially horizontal position at the top of the cabinet, and means for guiding said holders in their movements between the vertical position and the horizontal position 15 said guiding means being adapted to cause the lower ends of said holders to travel near the rear of said cabinet while moving between the vertical and horizontal positions and adapted to permit said holders to swing in vertical planes while 20 moving between the vertical and horizontal positions.

4. In a device of the class described, a cabinet for holding a group of holders, said cabinet having an inclined front wall extending downwardly and 25 backwardly from the top of the cabinet, holders adapted to lie in a substantially vertical position within said cabinet and being of greater length than the front to rear dimension of the upper portion of the cabinet, said holders being adapted 30 to be withdrawn in a horizontal position at the top of the cabinet, and means for guiding said holders in their movements between the enclosed position and the open position.

5. In a device of the class described, a cabinet 35 for holding a group of holders, holders adapted to lie in substantially vertical position within said cabinet and to be withdrawn into a horizontal position at the top of the cabinet, means against which the holders are adapted to rest and 40 to pivot, while moving from one position to another, and means for guiding said holders in their movements between the said vertical enclosed position and the open horizontal position.

6. In a device of the class described, a cabinet 45 for holding a group of holders, said holders adapted to lie in substantially vertical position within said cabinet and to be withdrawn into a horizontal position at the top of the cabinet, and a movable support at the top of the cabinet adapted to be projected beyond the cabinet and to form an 50 extended support for said holders when they are moved into the horizontal position.

7. In a device of the class described, a cabinet 55 for holding a group of holders, said holders adapted to lie in substantially vertical position within said cabinet and to be withdrawn into a horizontal position at the top of the cabinet, and a sliding cover for the top of the cabinet adapted to be projected to extend beyond the cabinet and to 60 form a support for said holders when they are in the horizontal position.

8. In a device of the class described, a cabinet 65 for holding a group of holders, holders adapted to lie in substantially vertical position within said cabinet and to be withdrawn into a horizontal position at the top of the cabinet, said holders comprising a bar or frame and leaves or trays 70 pivotally mounted thereon and adapted to be swung apart into horizontal position when said holders are moved into open position, and means for guiding said holders in their movements between the enclosed and open positions, said guiding means being adapted to cause the lower ends 75 of said holders to travel near the rear of said cabinet while moving between the horizontal and

vertical positions and adapted to permit said holders to swing.

9. In a device of the class described, a cabinet for holding a group of holders, holders adapted to lie in substantially vertical position within said cabinet, and to be withdrawn into a horizontal position at the top of the cabinet, said holders comprising a bar or frame and leaves or trays 80 pivotally mounted thereon and adapted to be swung apart in a horizontal position when said holders are moved into open horizontal position, and means for guiding said holders in their movements between the enclosed vertical and open horizontal positions and with which said holders remain connected when in their open position, said guiding means being adapted to cause the lower ends of said holders to travel near the rear of the cabinet and permit them to swing when moving between the vertical and horizontal positions. 95

10. In a device of the class described, a cabinet for holding a group of holders, holders adapted to lie in substantially vertical position within said cabinet and to be withdrawn and turned into a horizontal position at the top of the cabinet, 100 and members in said cabinet against which said holders are adapted to lean at different degrees of inclination as the holders are raised in said cabinet.

11. In a device of the class described a cabinet 105 for holding a group of holders, holders adapted to lie in substantially vertical position within said cabinet and to be withdrawn and turned into horizontal position at the top of the cabinet, means associated with the rear portion of said 110 holders for pivotally guiding the same during the movement of the holders, and members in front of said holders against which said holders are adapted to rest and to slide in various degrees of inclination during their movement into and 115 out of open position.

12. In a device of the class described, a cabinet adapted for holding a group of holders, holders adapted to lie in substantially vertical position within said cabinet and to be withdrawn and 120 turned into a horizontal position at the top of the cabinet, partitions in said cabinet dividing the same into a plurality of compartments, tracks on said partitions and pivotal means on said 125 holders and co-operating with said tracks where- by said holders are guided by said tracks in their movements into and out of said compartments.

13. In a device of the class described, a cabinet for holding a group of holders, vertical partitions 130 dividing said cabinet into a plurality of compartments, tracks mounted on said partitions and extending downwardly in said compartments, holders adapted to lie vertically in said compartments and to be raised and turned into a horizontal position at the top of the cabinet, means pivotally connected with one end of each holder and engaging said tracks and abutment means for guiding said holders in co-operation with said track during the movement of said holders into 135 and out of operative position.

14. In a device of the class described, a cabinet for holding a group of holders, vertically disposed partitions dividing the cabinet into compartments, tracks mounted on said partitions and having flanges, holders adapted to lie in vertical planes in said compartments and to be moved and turned into a horizontal position at the top of the cabinet, brackets secured to one end of 145 said holders and having sleeves pivoted thereto

and engaging the flanges of said tracks, and abutment means co-operating with said holders to guide the holders in their movements into and out of said cabinet.

5 15. In a device of the class described, a cabinet for holding a group of holders, holders adapted to lie in substantially vertical position within said cabinet and to be withdrawn and turned into a horizontal position at the top of the cabinet, tracks in said cabinet extending downwardly and

10 inclined toward the rear of the cabinet and thence curved forwardly toward the front of the cabinet, means on said holders pivotally connected to said tracks whereby one end of each holder is guided by a track, and abutment means co-operating to guide said holders whereby they are gradually turned into a horizontal position as they are raised to the top of the cabinet.
